UNITED STATES PATENT OFFICE.

EDWIN B. NATHAN, OF NEW YORK, N. Y.

COAT.

1,065,384.

Specification of Letters Patent. Patented June 24, 1913.

Application filed December 2, 1911. Serial No. 663,640.

To all whom it may concern:

Be it known that I, EDWIN B. NATHAN, a citizen of the United States, residing in New York, in the county of New York and State 5 of New York, have invented certain new and useful Improvements in Coats, of which the following is a specification.

This invention relates to wearing apparel, more particularly to coats, and has for its 10 object to devise a form of coat which can be worn in two styles, one having a box effect, and the other having a military effect and closely fitting around the waist.

A further object of this invention is to 15 devise a coat which may be tightened about the waist without the use of a belt, thus retaining the neat appearance of the military coat or of the present styles of sack coat.

20 A still further object of the invention is to form a coat with adjustable plaits which are situated in such a position as not to detract from neat appearance of the coat.

Further objects will appear from the 25 detailed description, and will be particularly pointed out in the claims.

In the accompanying drawing which illustrates my invention, Figure 1 is a perspective view of one form of my improved coat, and 30 showing it with the plaits in loose relation; Fig. 2 illustrates the form of coat shown in Fig. 1 with the plait partially tightened; Fig. 3 is a fragmental view illustrating the plait as substantially fully tightened; Fig. 4 is a section taken along the line 35 *a—a* in Fig. 1; Fig. 5 is a section taken along the line *b—b* in Fig. 3; Fig. 6 illustrates a modification.

1 indicates the front of a coat, and 2 indicates the back of a coat having preferably 40 a military collar 3, and adapted to be buttoned preferably in military fashion. At one side of the coat extending down from the arm pits is formed a plait having sections 4, 5 and 6, the sections 4 and 6 being adapted 45 to fold over the section 5, as illustrated in Figs. 3 and 5. A strap 7 is made fast to each edge of the back section adjacent to the waist, as at 8, and extends through a slit in the material adjacent to the front, as at 9. These straps 7 are adapted to be pulled tight about the waist and be fastened together in the form of a knot 10, or fastened with any other suitable fastening device. Stiffening sections 11, 12 and 13, 50 formed of leather or any other suitable ma-

terial, are provided on the respective plait sections adjacent to the straps, and serve to prevent the plait sections from wrinkling, and to cause them to fold over each other 60 smoothly. Another stiffening section 14 is provided on the interior of the front section of the coat and extends longitudinally of the stiffenings 11, 12, and 13. This section 14 forms a guide or loop through which the 65 strap 7 may be threaded and held in proper position about the waist. When the straps are tightened section 6 will fold over section 5, while section 4 is pushed back over the strap. By reason of the stiffenings 11, 70 12 and 13, the sections 4 and 6 will fold smoothly over section 5, producing the effect shown in Fig. 5.

The coat may be worn either entirely loose as shown in Fig. 1 and producing a loose 75 box effect, or it may be worn as shown in Fig. 3, with the straps tightened and the plait folded, thus producing a tightly fitting effect, such as obtained in the Norfolk coat. However, the numerous and conspicuous 80 plaits on the outside, and the conspicuous exterior belt characteristic of the Norfolk coat are entirely eliminated in my construction.

When designed with a military collar, the 85 coat will have a good deal of the appearance of the ordinary military coat, as the plaits are very largely hidden by the sleeves, and the straps are almost entirely hidden by the folding over of the plait sections.

In the modification illustrated in Fig. 6, the slit 17 is formed in the front of the coat for the purpose of allowing the strap 7 to pass through from the inside, and fasten on the outside substantially in the same 90 manner as in Fig. 5, or with any other suitable fastening. With this form of construction, the straps may be either fastened on the inside or outside as desired.

It is thus seen that I have produced a 100 coat which is adjustable about the waist and which still has the neat appearance of a box coat or of a military coat. The portions which are folded over in the process of adjustment are so located as to be almost entirely hidden and that portion which is 105 visible adds rather than detracts from the appearance of the coat. The adjusting element is almost entirely concealed, and thus does not detract from the appearance of the 110 coat, which corresponds outwardly to the present prevailing styles.

The coat is particularly adapted for use as an outing coat for sportsmen, hunters, trappers, etc. However, it is obvious that it may be used for uniforms of all kinds 5 and also for ordinary street wear.

I claim:

1. A coat having front sections and a back section, plaits between the front sections and back section, and a strap fastened at the exterior of the back section adjacent each plait, and passing through a slit 10 formed in the front section adjacent the plait and into the interior of the coat said straps being adapted to be fastened together 15 at the front interiorly of the coat.

2. A coat having an adjustable waist comprising a plait on each side, a strap fastened on the exterior of the coat at the waist line

adjacent to one edge of the plait and passing through the interior of the coat at a point 20 adjacent to the other edge of the plait, and stiffening means for each portion of the plait arranged adjacent to the strap.

3. A coat having an adjustable waist comprising a plait at each side, and a strap fastened to the exterior of the coat and passing through to the interior and adapted to adjust the plaits, stiffening means for the portions of the plaits, and a guide in the interior of the coat and extending longitudinally of the stiffening means and adapted 30 to have the strap passed therethrough.

EDWIN B. NATHAN.
